IMPACT MILL WITH CENTRIFUGAL
SEPARATIONEdwin Cowles, Cayuga, N. Y., assignor to The
Cowles Company, Princeton, N. J., a corpora-
tion of New Jersey

Application December 31, 1942, Serial No. 470,731

2 Claims. (Cl. 241—55)

1

This invention relates to mills for pulverizing, comminuting, triturating or otherwise reducing the size of pieces of solid material, preferably to a powdery or floury state.

It is an object of the invention to provide modifications and improvements on the mill disclosed in my copending application Serial No. 426,673, filed January 14, 1940.

Other objects and advantages of the invention will appear hereinafter.

A preferred embodiment of the invention selected for purposes of illustration is shown in the accompanying drawings, in which,

Figure 1 is a front elevation, with the front wall partly broken away, and partly in section on the line 1—1 of Figure 2.

Figure 2 is a side elevation, with the side wall partly broken away, and partly in section on the line 2—2 of Figure 1.

Figures 3 and 4 are similar views of a modified form, the sectioned portion of Figure 3 being on the line 3—3 of Figure 4, and the sectioned portion of Figure 4 being on the line 4—4 of Figure 3.

Referring to Figures 1 and 2 of the drawings, the apparatus comprises a casing 1 having a front wall 2, a rear wall 3, and a cylindrical shell 33 therebetween. The casing is designed for easy and rapid assembly and disassembly, and for this purpose is carried on a frame 4 having a face plate 34 to which the component parts of the casing are secured by means of bolts 35. The frame also serves as a support for the shaft 5, said shaft being carried in bearings (not shown) in a housing 6 forming an integral part of the frame. The shaft may be driven in any suitable manner, as by a pulley 7 mounted on one end thereof. The other end of the shaft extends into the casing, and carries a grinding material secured thereto as hereinafter described and adapted to rotate therewith.

In the preferred embodiment illustrated the said grinding member comprises a plurality of grinder bars 8 having peripheral grinding surfaces 9. The said bars are welded or otherwise secured to annular rings 11 and 12, and the resulting assembly may be secured by bolts 13 to a flanged hub 14 secured to the shaft 5 by a nut 15.

The interior of the casing, opposite the peripheral grinding surfaces, is spaced from said surfaces, but is provided with spaced bars 16 held in grooves in the shell 33, and extending transversely across the casing, which said bars are also spaced from the grinding surfaces.

In the embodiment illustrated, the bars 8 are

2

somewhat larger than necessary to provide adequate structural strength, in order that the inner part of said bars may serve as vanes or paddles tending to whirl the material in the chamber between the grinding surfaces and the discharge opening 3 through which the ground material is discharged. Said vanes establish and maintain a centrifugal separating action in said chamber tending to return the larger pieces of material to the zone of grinding action and allowing only the more finely ground material to be discharged. Thus, in addition to their grinding function, the bars 8 are constructed and arranged so that part of said bars may perform the functions of the centrifuging vanes of my copending application above referred to.

In this connection, the stationary bars 16 may again be referred to. It will be observed that the arrangement of the said bars is such as to retard the movement of material along the inner wall of the shell 33, so that the material in what may be called the grinding zone, i. e., the space between the grinding surfaces 9 and the inner wall of the casing, does not partake of the whirling movement of the material in what may be called the centrifuging zone, i. e., the space or chamber between the grinding surfaces and the outlet opening. Thus there is an effective separation of the two operations of grinding and centrifugal separation or selection, and such separation improves the effectiveness of both operations. For example, it will be understood that the grinding action is partly due to impact and partly due to attrition. By retarding the movement of the material in the grinding zone, not only is the impact of the rotating bars on the retarded material greater than would be the case if that material were moving more rapidly, but also the impact of the material rebounding from the rotating bars against the retarded material is greater than if that material were moving more rapidly. Similarly, of course, the attrition effect between the rotating bars and retarded material is greater than if the material in the grinding zone were moving more rapidly.

The bars 8 are also arranged, as shown, in such manner that their front faces are inclined to a radius passing therethrough in such manner that the inner portions are advanced. This has the effect of restricting the passage between adjacent bars, thus tending to trap the larger pieces and prevent them from moving toward the discharge opening until further reduced in size. It also has the effect of causing pieces of material which are struck by the advancing faces of the bars to move

outwardly rather than inwardly toward the discharge opening.

In the preferred embodiment illustrated a pair of annular rings 37, 38 are mounted in the casing opposite the ends of the bars 8 and having a loose running fit therewith. Such rings serve to restrain material in the grinding zone from moving toward the discharge opening along the ends of the bars where the centrifugal action is least effective. If desired the bars 8 may be provided with notches 39 registering with annular projections 40 on the rings 37, 38 which further improves the restraining action by causing any particles which tend to move inwardly to be deflected by the projections 40 into the path of the vane portions of the bars 8. It will be understood that the casing walls 2 and 32 might be arranged to have a loose running fit with the ends of the bars 8 and thus serve the purpose of the rings 37, 38. However, considerable wear occurs due to abrasion and the rings are easily replaceable as wear occurs.

In the operation of the machine, material to be ground is fed into the machine through the inlet passage 24 in the wall of the shell 33, said passage being arranged substantially tangentially to the path of the bars 8. Since the action of the vane portions of the bars 8 acting alone would tend to pump air backwardly so as to discharge partially ground material through the inlet passage, the machine is used in combination with a blower to circulate air through the machine toward the discharge opening.

In operation, the grinding member is preferably rotated at velocities considerably lower than described in my copending application before referred to, the particular velocity selected depending on the nature of the material and the particle size desired. For example, good results may be secured in grinding easily frangible materials at velocities as low as 400 linear feet per minute at the periphery. Grinding occurs partly by attrition and partly by impact, but due to the centrifugal action previously described, only finely ground material escapes to the discharge opening.

In this connection, it will be understood that particle size is dependent, not only on the velocity of the rotating member, but also on the velocity of the current of air induced by said blower. The higher the velocity of the latter, the larger will be the size of the particles discharged, assuming that the velocity of the rotating member remains the same. Thus, by balancing the velocity of the rotating member against the velocity of the current of air, the particle size discharged may be controlled.

A modified form of machine is shown in Figures 3 and 4 in which the grinder bars 8' having grinding surfaces 9' are of a size merely sufficient to provide adequate structural strength, and hence exert little or no centrifugal selecting effect. In this form of machine, therefore, separate centrifuging vanes 26 are provided, which said vanes are mounted on a disk 42 secured to the shaft 5' for rotation therewith, said disk being spaced from the wall of the casing to provide a passage therebetween in which said vanes operate. In this form of machine, the ring 38' extends somewhat closer to the discharge opening 3' and has a loose running fit with the edges of the vanes 26 in order to restrain the passage of material toward the discharge opening along the edges of the vanes. As before, the vanes and ring may be provided with registering notches 39'

and projection 40' to further improve the restraining action.

Stationary bars 16' are also provided in the modified form of machine and serve the same purposes as in the form shown in Figures 1 and 2. However, because of the wide separation between the grinding zone and the centrifuging zone in the modified form it is advisable in some cases to provide additional means to retard whirling movement between the two zones. For this purpose, the ring 38' may be provided with a plurality of stationary fins 43 which reduce the whirling in the chamber and hence reduce the centrifugal separating effect within their zone of effective action, and particularly at the entrance to said passage. Thus the principal centrifugal effect is exerted by the vanes 26 alone.

The modified form of machine of Figures 3 and 4 is designed to be capable of operation at velocities higher than those of the machine of Figures 1 and 2. The machine is thus available for use in grinding materials which require more severe attrition or heavier impact in order to be reduced to the desired particle size. In both the machine of Figures 1 and 2 and the machine of Figures 3 and 4 it will be understood that the higher the velocity, the greater the centrifugal effect, and in the machine of Figures 1 and 2 when the machine is run at velocities sufficiently high to secure efficient grinding of certain materials, the centrifugal effect is so great that the discharged particle size is too small. In the machine of Figures 3 and 4, however, the arrangement is such as to permit the use of higher velocities while at the same time reducing the centrifugal effect by locating the centrifuging vanes nearer to the axis of rotation. Thus by proper selection of machine, velocity of rotating member, velocity of air flow and vane locations, a wide range of materials may be reduced to desired particle size.

It will be understood that the invention may be variously modified and embodied within the scope of the subjoined claims.

I claim as my invention:

1. A mill comprising a casing, a grinding member mounted for rotation in said casing, said grinding member having peripheral grinding surfaces spaced from the surrounding wall of the casing to provide a grinding zone therebetween, said casing having intake and discharge openings, vanes located between said grinding surfaces and said discharge opening to whirl the ground material moving from said grinding surfaces toward said discharge opening to centrifuge the same, said vanes having notches formed in their side edge, and stationary annular means carried by said casing opposite the side edges of said vanes and projecting into said notches to deflect ground material moving between the ends of said vanes and said casing toward said discharge opening into the path of said vanes.

2. A mill comprising a casing, a grinding member mounted for rotation in said casing, said grinding member having a plurality of grinder bars having peripheral grinding surfaces spaced from the surrounding wall of the casing to provide a grinding zone therebetween, said grinder bars being spaced to provide passages therebetween through which ground material may move from the grinding zone toward the axis of rotation of said member, stationary bars mounted in the surrounding wall of the casing and spaced radially from the peripheral grind-

ing surfaces of said grinder bars and projecting into said grinding zone to retard whirling movement of material therein, said casing having intake and discharge openings, said grinder bars having a portion thereof between said grinding surfaces and said discharge opening and extending across the space providing communication therebetween serving as vanes to whirl all of the

5 ground material moving between said bars toward said discharge opening to subject the same to substantially uniform centrifuging action, the front faces of said grinder bars being inclined in such manner that the inner portions are advanced.

EDWIN COWLES.
